1 Claim

ABSTRACT OF THE DISCLOSURE

An air-depolarized battery of the type having a carbon cathode with one or more cavities leading through the top face to a lower portion thereof is provided with a wire coil in each cavity which is inserted under tension so that when released it springs out to engage the cavity wall under pressure. The coil provides a low resistance connection continuously throughout the height of the cathode from the lower portions closed to the active interface of the cathode with the electrolyte to the upper portion engaged by the cathode terminal. Preferably, the coil has also an upper tail extension connected to the cathode terminal for providing a direct connection of the terminal with each such lower portion of the cathode.

An object of the invention is to provide an air-depolarized battery having increased efficiency and greater ampere output.

Another object is to provide an improved low-resistance terminal connection to an air-depolarized cathode.

A further object is to provide a novel electrode connection to an air-depolarized cathode which is continuous throughout the height of the cathode and in proximity with the interface between the cathode and the electrolyte.

These and other objects and features of the invention will be apparent from the following description and the appended claims.

FIG. 1 is a vertical section on a medial plane through an air-depolarized battery incorporating the invention; and FIG. 2 is a vertical section on the line 2—2 of FIG. 1.

The battery illustrated in the accompanying drawings has a rectangular case 10 as of acrylic plastic material comprising a lower rectangular container 11 and a cover 12 seated on and sealed to the rim of the container. The cover has depending flanges 13 receiving plastic holders 14 in sealed relation thereto for a pair of spaced zinc anodes 15, and has a carbon cathode 16 spaced midway between the zinc anodes. The carbon cathode is supported from the cover 12 by a plastic hanger 35 and is sealed along its rim to the cover by a suitable sealing compound 36 such as of pitch. An opening 17 in the cover inset from the rim of the cathode exposes the top face of the cathode to a rectangular air compartment 18 bounded by side and end walls 19 and 20 upstanding from the cover and by a top cover plate 21. In the end walls 20 there are openings 22 to the atmosphere and on the top cover plate 21 there are stacks 23 with side openings 24 to the atmosphere. These openings permit a passage of air from the atmosphere through the air compartment into direct contact with the carbon cathode 16.

The carbon cathode is provided with one or more cavities 25—four being shown by way of example—which extend through the top face of the cathode downwardly to the bottom portion thereof so as to permit a flow of air to portions of the cathode close to the interface thereof with the electrolyte. Additionally, the battery is desirably provided with a chimney system as is described in my co-pending application filed July 17, 1972 and entitled Air-depolarized Primary Battery, to augment the flow of air

2

from the outside atmosphere to the bottom portions of the cavities. However, such chimney system need not necessarily be employed with the present invention and is not herein described.

5 The present invention takes advantage of the provision of the air cavities in air-depolarizing cathode electrodes to obtain a low-resistance electrical connection with the cathode whereby a markedly higher voltage and ampere output are obtained from the battery. This is accomplished by inserting a wire coil 26 into each cavity from the bottom portion thereof to the top thereof. The coil is made of low resistance wire such as of copper, but whatever material is used is desirably also of a springy character so that the coil will engage the wall of each cavity under pressure. For this purpose each coil is made to have a normal outside diameter suitably larger than the diameter of the cavity into which it is to be placed, and the coil is tensioned or wound inwardly on itself to reduce its outside diameter so that it can be readily inserted into the cavity. After the coil is inserted it is released to spring outwardly and engage the wall of the cavity under pressure on a continuous helical line from the bottom portion of the cathode to the top thereof.

20 The provision of such coil in each cavity has the advantage that it provides a low resistance direct connection continuously throughout the height of the cathode to the portion of the cathode surrounding each cavity to reduce the resistance to current flow from each portion of the cathode having an interface with the electrolyte to the upper portion of the cathode engaged by the terminal of the battery. To reduce still further the resistance to current flow from the active portions of the battery having an interface with the electrolyte to the cathode terminal each wire coil is provided with an extending tail 26 at its upper end which is led across the top of the carbon cathode to the center of the battery whereat it is soldered to an apertured lug 28 of a washer 29. A terminal post 30 for the cathode is extended through the top cover plate 21 and sealed thereto by clamping pressure of a nut 31 threaded onto the post to exert pressure through a sealing washer 32 onto the surrounding portion of the top plate 21 backed by a stop nut 33 on the post. The terminal post 30 then extends further through the washer 29 and into the upper part of the cathode. Above the washer 29 there is a pair of nuts 34 tightened to clamp the washer against the upper face of the carbon cathode with the upper nut being tightened against the lower one in a locking relationship. Thus, a metallic low-resistance connection is obtained between the terminal post and every portion of the cathode in close electrical contact with the electrolyte. This metallic connector of the terminal post continuously throughout the height of the cathode with every portion in close active relationship with the electrolyte circumvents the need for the current from the interface between the cathode and the electrolyte to flow through any substantial portion of high resistance cathode material. Thus, a higher output voltage is obtained and electrical losses within the battery are reduced to increase the amperes output of the battery.

25 The embodiment of my invention herein particularly shown and described is intended to be illustrative and not necessarily limitative of my invention, since the same is subject to changes and modifications without departure from the scope of my invention, which I endeavor to express according to the following claim.

I claim:

30 1. An air-depolarized primary battery comprising an electrolyte solution, an anode in said solution, a carbon cathode partially immersed in said solution and having a plurality of vertical cavities therein extending through the top face thereof to the bottom portion thereof, said cavities being cylindrically shaped, a helix wire of a conduc-

tive spring material inserted in each of said cavities throughout the length thereof, each of said wire helices having normally a larger outside diameter than the diameter of said respective cavity causing the wire helix to exert a radial pressure against the wall of the cavity and provide a continuous firm engagement of the helix on a helical line with said cathode, a terminal post anchored into an upper portion of said cathode between said cavities in electrically conductive relationship with the cathode, a lead wire extending from and electrically connected to each of said wire helices, and means electrically connecting each of said lead wires to said terminal post.
